UNITED STATES PATENT OFFICE.

BALERA J. AURAND, OF MANSFIELD, ASSIGNOR OF ONE-HALF TO HALSEY
H. RUDD, OF CLEVELAND, OHIO.

THILL-TUG.

SPECIFICATION forming part of Letters Patent No. 269,989, dated January 2, 1883.

Application filed August 20, 1881. Renewed June 1, 1882. (No model.)

To all whom it may concern:

Be it known that I, BALERA J. AURAND, of Mansfield, in the county of Richland and State of Ohio, have invented a new and useful Improvement in Thill-Tugs, of which the following is a specification, reference being had to the accompanying drawings.

The invention relates to an improved thill-tug for shafts; and it consists in the novel construction and assemblage of the parts composing same, as hereinafter described, and particularly pointed out in the claim.

Referring to the accompanying drawings, Figure 1 is a side view, Fig. 2 is an edge view, and Fig. 3 is a central vertical section, of the thill-tug. Figs. 4, 5, 6, 7, and 8 are detached views, illustrating the construction of the different parts of the thill in detail, and herein-after referred to by letter.

A denotes the core of the thill-tug, which consists of a piece of metal either cast into or otherwise given the proper form. The outer surface of core A will preferably be flat, and its inner surface beveled or rounded; but this is not essential to the successful production of the article. The ends of the core A are threaded, as shown, and at its center is hung the loop B. That part of the core upon which the loop hangs is squared, so that the latter, which has an aperture of corresponding form, cannot turn or become loose. Upon the core A are placed the pieces of leather, wood, rubber, or other material, D, a sufficient number being employed to cover the entire surface of the core up to the lower portion of its threaded ends a. The pieces D will preferably be strung upon the core A and pressed closely together, so as to form a firm covering, and after being secured by the cap E, as hereinafter specified, are cut or trimmed to the desired size or form,

according to the wish of the manufacturer. After the pieces D have been placed upon the core A, the cap E is inserted by means of the holes b upon the threaded ends a, and the nuts d applied for retaining the same in place. The cap E will preferably be of cast metal, having the holes b in its flat base, the corresponding grooves, e, at its upper rounded edges for the reception of the buckle, and the threaded apertures f in its ends in order to receive the screws h, which secure the other parts of the thill in place. After the cap E has been secured in position by the nuts d, as aforesaid, the buckle m and box-loop n are applied and effectually held in proper relation to each other by the metallic strip H, which is first passed over the tongue of the buckle, the latter being then settled into the grooves e, after which the box-loop n is inserted over the long end of the strip H, and the whole secured in place, substantially in the manner shown, by the screws h.

The thill tug thus produced is strong and durable, is quickly and easily made, and is not liable to get out of order.

What I claim as my invention, and desire to secure by Letters Patent, is—

A thill-tug consisting of the core A, having ends a and a covering of rubber, leather, or other material, the cap E, secured upon said ends, and the strip H, holding the buckle and strap-loop in place, substantially as specified.

In testimony that I claim the foregoing improvement in shaft-thills, as above described, I have hereunto set my hand this 27th day of June, 1881.

BALERA J. AURAND.
